WINDOW SHELF OR SIMILAR ARTICLE

Karl T. Wright, Cuyahoga Falls, Ohio

Application December 22, 1949, Serial No. 6,776

Term of patent 14 years

(Cl. D33—3)

To all whom it may concern:

Be it known that I, Karl T. Wright, a citizen of the United States and a resident of Cuyahoga Falls, in the county of Summit and State of Ohio, have invented a new, original, and ornamental Design for Window Shelf or Similar Article, of which the following is a specification, reference being had to the accompanying drawing, forming part thereof.

In the drawing:

Figure 1 is a front perspective view, of a window shelf or similar article showing by new design.

Figure 2 is a rear perspective view with a portion of the border being indicated by marginal dotted lines, it being understood that the border is continued throughout the margin of the shelf.

What I claim is:

The ornamental design for a window shelf or similar article, as shown and described.

KARL T. WRIGHT.
